UNITED STATES PATENT OFFICE.

WILLIAM SUTTON, OF ST. LOUIS, MISSOURI, ASSIGNOR TO THE LA CLEDE CAR COMPANY, OF SAME PLACE.

REVERSIBLE CAR-SEAT.

SPECIFICATION forming part of Letters Patent No. 389,174, dated September 4, 1888.

Application filed May 10, 1887. Serial No. 237,748. (No model.)

To all whom it may concern:

Be it known that I, WILLIAM SUTTON, of the city of St. Louis in the State of Missouri, have invented certain new and useful Improvements in Reversible Car-Seats, of which the following is a full, clear, and exact description, reference being had to the accompanying drawings, forming part of this specification, and in which—

10 Figure 1 is a back view of one of my seats, part in section. Fig. 2 is a transverse section at 2 3, Fig. 1, showing the seat in position for use. Fig. 3 is a transverse section at 2 3, Fig. 1, showing the seat in the reversed position to that shown in Fig. 2.

This invention relates to sliding reversible car-seats; and the invention consists in features of novelty hereinafter fully described, and pointed out in the claim.

20 Referring to the drawings, in which similar letters of reference indicate like parts, A A are the supporting metallic ribs, which, in conjunction with a middle metallic strap, B, support the combined seat and back.

25 C is the seat proper, which is preferably constructed of strips of wood or rattan; but it may be made of any other suitable material. The said seat may be secured to the ribs and strap by rivets or by any other suitable means.

30 D represents the uprights or ends, D' the feet, and E the transverse connecting-bars of the frame that carries the seat. The said vertical and horizontal parts of the frame are secured together in metallic union boxing F, in the 35 square sockets of which they engage.

G represents bracket-clips, that are bolted or otherwise fastened to the horizontal bars of the frame. The twin horizontal hooks G' of the clips engage in the grooved ways H' on the 40 sides of guide-brackets H, that are securely bolted or otherwise attached to the metallic ribs A.

It will be seen that by reason of the horizontal hooks G' of the clips being in engagement 45 with the guide-brackets on each side in the

grooved ways H' the combined seat and back cannot be disengaged from the uprights by reason of any lateral strain which might be brought to bear upon either the uprights or the seat and back. 50

G² represents pins, that rise vertically from the middle of the bracket-clips and enter perforations G³ in the bracket-guideways when the combined back and seat have reached either of the positions at which it is desired to bolt 55 or lock it. A slot, G⁴, is also made through the rib and penetrates the under surface of the combined seat and back to give place to the bracket-clip when the seat is locked.

The upper and lower parts of the combined 60 seats and backs are counterparts of each other, so that as they are reversed they exactly adapt themselves to the position previously held by the other part.

The operation of my reversible sliding back 65 and seat is as follows: The seat is slightly raised to the extent the clip-hooks will allow, so as to force the locking-pins from the apertures in which they engage, and is then slid into its reversed position, the clip-hooks following in the grooves of the guideways, and the locking-pins then enter other perforations provided to fasten them in their new position. 70

I claim as my invention—

In combination with a reversible seat and 75 back having guide-brackets H, provided with grooved ways H' on each side and having vertical perforations, the supporting-frame having bracket-clips G, fixed thereto, twin hooks G' of the clips adapted to engage in the grooves 80 on each side of the brackets, and pins G², rising vertically from the bracket-clips from between the twin hooks and adapted to enter a single perforation in each of the brackets, substantially as and for the purpose set forth.

WILLIAM SUTTON.

In presence of—

BENJN. A. KNIGHT,
SAM'L. KNIGHT.
